(57) **CLAIM**

The ornamental design for a combined knife and scissor holder as shown and described.

DESCRIPTION

FIG. 1 is a left side, top perspective view of a combined knife and scissor holder showing my new design.

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines showing portions of the combined knife and scissor holder in the drawings form not part of the claimed design.

1 Claim, 7 Drawing Sheets
